UNITED STATES PATENT OFFICE

GEORGE A. MACREADY, OF LOS ANGELES, CALIFORNIA

APPARATUS FOR MAKING PRODUCTION TESTS IN WELL DRILLING

Application filed July 25, 1922. Serial No. 577,433.

In my application filed July 5, 1922, Serial No. 572,889, I disclosed a new method and apparatus for facilitating the making of production tests of the lower portions of deep wells so as to determine the proper point at which the well is to be sealed so as to cut off water from above the oil bearing strata.

This invention relates to improvements in my apparatus as above referred to.

10 It is an object of the present invention to provide means for shutting off water and for maintaining a circulation in the apparatus preparatory to making a production test so as to insure the recovery of the apparatus by 15 keeping it from being frozen in the well or jammed. Further to provide an apparatus in which there is utilized an inner circulating pipe and an outer circulating pipe, the latter being capable of constant rotation during the production test. Another object is to 20 provide means for the washing of the well by adding clean water during the lowering of the testing apparatus to a previously formed packer seat. An object also is to provide 25 means whereby the washings from the well during the lowering of the packer may pass between an inner and an outer pipe and prevent the scouring of the wall of the well above the packer; means being provided for the 30 rotation of the outer pipe while washing circulation is maintained. It is, therefore, broadly an object of the invention to provide for a washing circulation in which the discharge water from the well passes up in 35 through the apparatus and not directly along the well wall.

Another object is to provide an apparatus for facilitating production tests and for aiding in determining the permanent sealing zone, and which apparatus includes a packer engageable with a formed seat and which packer is connected to a circulating and a sample taking pipe, and to provide about 40 such pipe a constantly rotatable circulating pipe providing means whereby the packer may be recovered after performance of function.

Other objects and advantages will be made 45 manifest in the following specification of an

embodiment of the invention illustrated in the accompanying drawings, in which

Figure 1 is a diagrammatic vertical longitudinal section of the apparatus in the step of being lowered to a temporary sealing position. 55

Fig. 2 is a longitudinal vertical section of the apparatus in its effective sealing and circulation maintaining position.

Fig. 3 is a longitudinal central section of 60 a portion of one form of packer string.

Fig. 4 is a cross section on line 4—4 of Fig. 5, showing the wall penetrating points.

Fig. 5 is a central longitudinal section of 65 a modified form of the packer string.

Fig. 6 is a central longitudinal section of a form of swivel head for the packer string.

Fig. 7 is a cross section on line 7—7 of Fig. 6.

Fig. 8 is a cross section on line 8—8 of 70 Fig. 6.

Fig. 9 is a cross section on line 9—9 of Fig. 6.

The invention is embodied in an apparatus including a string of pipes and a packing 75 section at the foot thereof and a stationary swivel case at the head thereof, and in the preferred form the apparatus is capable of being bodily lowered, excepting the swivel top mechanism, into a well casing 2 of suitable diameter and at the top of which is a stuffing box 3, Fig. 1, surrounding an outer pipe 4 of such diameter as to form a suitably sized cylindrical passageway within the casing 2. 80

It is understood that the packing string may be of any suitable number of sections of desired size according to the given conditions, and the topmost section of the outer pipe 4 is shown in Fig. 6 as extending upwardly into a substantial block or swivel case 5 which has its lower end internally bored and threaded at 6 to receive the top section 4, and about which there is compressed a ring of packing 7 engaged by a packing gland 8 which is secured by a lock gland 9. This secures a water tight operating joint as between the top section 4 and the case. 95

The swivel case 5 is provided with an open upper end and forms a suitable chamber 10

which is closed as by a retaining cap 11 which may be secured as by cap screws 12 mounted on the rim of a case 5. This latter is shown as provided with diametrically opposite trunnions 13 to be engaged by any suitable elevating and suspending means for such period of time as may be necessary in lowering the apparatus into the well hole after which the case 5 is lowered to a suitable support, as for instance a set of supporting beams 14, Fig. 2.

This enables the throwing of the elevating mechanism of the string out of connection and facilitates the application of other appurtenances, as for instance to connect a small 15 swivel of circulating pipes to the top of an inner pipe 15. This also provides for the step of bailing the well through the inner pipe 15 when the swivel case 5 is stationary on a permanent support.

20 A form of mechanical construction providing for the rotation of the top pipe section 4 includes an annular shoulder $4\frac{1}{2}$ provided on this top section, and this is lowered onto a set of ball bearings or other antifriction devices 25 16 arranged in the swivel case to take the weight of the parts connected to the shoulder $4\frac{1}{2}$. Upthrust bearings 17 are provided on the shoulder $4\frac{1}{2}$, and these bear against a head block 18 which is fastened as by cap 30 screws 19 to a shoulder provided therefor in the case 5. The top pipe section 4 extends up through the block or head 18, and the latter is provided with a hub portion $18\frac{1}{2}$ internally threaded to receive packing members 75 for compressing a packing ring 20 surrounding the contiguous portion of the pipe 4.

Circulation into and from the swivel case chamber 10 is provided by any suitable connection as a lateral coupling 21 which may be connected to the circulation pumps or otherwise as may be necessary so that water can be forced down in the outer pipe 4 or can flow up through the outer pipe 4.

The inner pipe 15 is built up of a suitable 45 number of connected sections, the topmost of which passes up through the cap 11 and is packed therein by packing members 22 and 23 compressing a packing ring 24. The head pipe section 15 is of sufficiently small diameter 50 to provide an ample passageway 25 within the pipe section 4, and preferably the top pipe section 15 is provided with an operating bearing and guide means at the lower end of the top section 4. Such means is here 55 shown as including a plurality of radial ribs $15\frac{1}{2}$, Fig. 9, spaced sufficiently to provide ample passageway for the water and being of such length as to give efficient guide and bearing surfaces.

60 The top sections of pipes 4 and 15 may preferably terminate even with each other below the swivel case 5 and thus provide for the ready attachment and disconnection of the subjacent sections during operation.

65 A preferred form of packing means is

shown in Fig. 5 as including the necessary inner and outer pipes 15 and 4, and to the lower end of these pipes the packing elements are attached. The lowermost outer pipe 4 is threaded into the upper end of a substantial bearing sleeve 30 which is provided with an internal shoulder 31 somewhat below its upper end, and the lower end of the bearing sleeve 30 is turned down as at 32 to a suitable diameter.

The inner string of pipe 15 includes a foot section of hollow spindle 33 having a thickened body portion $33\frac{1}{2}$ terminating in a shoulder $33\frac{1}{4}$ bearing on the shoulder 31 of the bearing sleeve 30. The upper end of the spindle body $33\frac{1}{2}$ is externally threaded so as to receive a packing gland 34 compressing a packing ring 35 against the contiguous surface of the bearing sleeve 30 and thus forming a watertight joint. The hollow spindle passes down and rotatably fits in the bearing sleeve 30, and below the end of the sleeve is arranged a ball or other antifriction bearing 36 supported on an internal shoulder provided therefor in a packer body 37 into which the lower end of the hollow spindle 33 is threaded at $37\frac{1}{2}$ so as to be securely attached thereto. The body of the packer extends upwardly and is counterbored to receive a packing gland 38 for compressing a packing ring 39 against a rotating surface of the interposed bearing sleeve 30.

The packer body has an effective packing exterior lower portion which is preferably tapered so as to form a good seal upon a previously cut seat prepared therefor in the well hole, and in the present case the lower end of the packer body 37 is turned down and is provided with a series of longitudinally spaced rings or shoulders $37\frac{1}{4}$ below which the lower end of the packer body is externally threaded as at $37\frac{3}{4}$ to be attached to a small central sample taking pipe, not shown, which can be entered into a small well hole cut therefor at the bottom of the well.

The reduced portion of the body 37 of the packer is suitably embedded in or surrounded by any desirable material having the property of making a good tight seat with the well wall, and this packing material is indicated at 40. It is built up to any desired degree of thickness and it is retained in place against longitudinal shifting, under the superimposed load, as by the shoulders $37\frac{1}{4}$ provided therefor. If desired, to insure against rotation of the packer, the body may be provided with substantial projections or penetrating points 41 to engage the contiguous wall or seat in the well hole and thus lock the packer in place against turning.

A slightly modified form of the packing apparatus is shown in Fig. 3. In this form the inner pipe spindle 33 is provided with an enlarged intermediate body portion $33\frac{1}{2}$ forming an upper shoulder upon which rests

a ball bearing 33^a which in turn presses up against a contiguous shoulder provided on the upper body portion of the bearing sleeve 30 in and through which the upwardly extending and reduced-spindle 33 passes. Attached to the lower end of the sleeve 30 is a locking sleeve 45 threaded at 46 onto and in the lower end of the bearing 30, and this locking sleeve 45 extends upwardly and engages the contiguous end shoulder of the body 33^{1/2} of the spindle 33 so that the bearing 30 and the lock sleeve 45 are joined together and rotated relatively upon the innermost hollow spindle 33. The lower end of the lock sleeve 45 is internally counterbored and threaded to receive a locking gland 47 for compressing a packing ring 48 therein. The hollow spindle 33 extends below the end of the locking sleeve 48 and is threaded in the upper end of the body 37 of the packer as herein previously described.

From the above it will be seen that when the elevating and suspending bail device B, Fig. 1, is attached to the swivel case trunnions 13, the whole string of inner and outer pipes 15 and 4 are carried by the casing swivel and the outer pipe is adapted to be rotated by the usual rotary table R of a rotary drilling apparatus. While the string of packer elements are being lowered into the well, rotation can be maintained by the rotary table R of the outer pipe 4, while the inner pipe and the packer attached to the packing spindle 33 thereof being connected by a swivel joint at the bottom of the string in the bearing 30 does not rotate. During the lowering of the string, circulation is maintained by a flow of circulation fluid entering the top of the inner pipe 15, thence down to the bottom of the inner pipe where it discharges freely into the well and passes up to the surface thereby preventing the pipe from sticking. Just before seating of the packer, circulation is maintained as by a flow of water entering the top of the inner pipe 15, and thence down to the bottom of the inner pipe where it discharges freely into the well and passes up outside of the lower inner pipe and around the packer 37 as is shown in Fig. 1, and thence up until the water may find access into the outer pipe 4. This access and escape from the well hole is provided by a series of apertures 4^a in the lowermost section of the pipe 4 and just above the foot swivel and bearing member 33. The stuffing box 3, being closed, prevents the water from going up outside of pipe 4 thereby avoiding scouring the walls of the hole. The upwardly flowing water passes freely into the space between the inner pipe 15 and the outer pipe 4 and thus does not rise along the well wall and the scouring of the wall is prevented above the packer. The water entering the pipe 4 passes to the top thereof and escapes through the lateral connection 21 as indicated in Fig. 1.

When the packing string has been lowered to the necessary position, the packing facing 40 engages the seat S provided therefor in the well hole and becomes fixed and solidly seated and is held against rotation either by friction upon the seat or by the interlocking of the holding prongs 41 engaging in the wall. As soon as the packer has become seated, it will be seen that upflow from below is prevented except through the innermost or central pipe 15. This is open continuously from top to bottom and provides for the bailing of the bottom of the well and for such other steps as may be taken in the production test.

When the packer is seated, mud circulation 80 may be maintained from the pump system by forcing the fluid into port 21 of the swivel case at the head of the well wall when this is seated on its permanent supports 14. The fluid is forced down through the space between the inside pipe 15 and the outside pipe 4 and discharges outwardly through the openings 4^a and passes upwardly along the surface of the well and plasters the wall above the packer. The upwardly flowing circulating 90 mud is discharged through the well casing at the head of the well.

It will be seen also that the weight of the columns of pipes upon the seated packer can be readily regulated by the amount of weight of the swivel head and apparatus that is super-imposed on the permanent supports 14 upon which the swivel case is lowered after the packer has become seated. The advantage of this is that considerable strain is removed 100 from the packer and also from the string of pipe sections and their joints throughout the string.

This construction provides for the constant rotation of the outer pipe string 4 while it is being lowered into the hole and after the packer has become firmly seated and provides also for the downward or upward circulation or flow of liquid in the space between the two pipes, and all of this with the object of 110 insuring the possibility of recovering the apparatus from the well.

Further embodiments, modifications and changes may be resorted to within the spirit of the invention as here claimed.

What is claimed is:

1. An apparatus for making production tests in drilled wells, comprising a hollow swivel case, there being a passage for fluid provided on the case, an outer rotary pipe, an inner hollow spindle extending through said case and down through said outer pipe, and carrying a packer at its lower end below the outer pipe, and which packer is adapted to be rested temporarily upon a previously formed seat in the well, said outer pipe having adjacent to its lower end inlet and outlet openings for fluid to provide for discharge or entry of fluid from and to the outer pipe.
2. An apparatus for obtaining fluid from

- a drilled well comprising inner and outer pipes, a packer connected to the outer pipe and having a passage therethrough communicating with the inner pipe, said inner pipe 5 and passage cooperating to form a straight, continuous, unobstructed conduit from the bottom of the packer upwardly, there being discharge ports adjacent the bottom of the outer pipe, whereby well fluid may be withdrawn 10 through the seated packer and through the inner pipe while circulation fluid is forced downwardly within the outer pipe about the inner pipe and discharged therefrom above the seated packer.
- 15 3. An apparatus for obtaining fluid from a drilled well comprising inner and outer pipes, a packer movably connected to the outer pipe and having a passage therethrough communicating with the inner pipe, whereby fluid may be withdrawn through the seated packer and the inner pipe while the outer pipe is being moved, there being discharge ports adjacent the bottom of the outer pipe so that circulation fluid may be forced downwardly within the outer pipe about the inner pipe and discharged above the seated packer 25 during the movement of the outer pipe.
4. A flow tester comprising inner and outer pipes, a packer connected to the outer pipe having a passage in communication with the inner pipe, said inner pipe and passage cooperating to form a straight, continuous, unobstructed conduit from the bottom of the packer upwardly, there being ports providing for the discharge of circulation fluid through the outer pipe around the inner pipe.
5. An apparatus for making production tests in deep well drilling comprising an outer pipe, a packer having a passage therethrough and which is capable after having once been seated in a well of retaining its sealing effectiveness independently of forces exerted upon it by the outer pipe, means cooperating with the packer for forming a conduit extending from the bottom of the packer upwardly within the outer pipe, and means including an anti-friction bearing providing a movable connection between the packer and the outer pipe enabling the outer pipe to be moved 50 while the packer remains seated without disturbing the seated packer.
6. An apparatus for making production tests in deep well drilling comprising an outer pipe, a packer having a passage therethrough and which is capable after having once been seated in a well of retaining its sealing effectiveness independently of forces exerted upon it by the outer pipe, means cooperating with the packer forming a conduit extending from the bottom of the packer upwardly within the outer pipe, means providing a movable connection between the packer and the outer pipe enabling the outer pipe to be moved while the packer remains seated without disturbing the seated packer, and means associated with the

7. An apparatus for making production tests in deep well drilling comprising an outer pipe, a packer having a passage therethrough and which is capable after having once been seated in a well of retaining its sealing effectiveness independently of forces exerted upon it by the outer pipe, means cooperating with the packer forming a conduit extending from the bottom of the packer upwardly within the outer pipe, means providing a movable connection between the packer and the outer pipe enabling the outer pipe to be moved while the packer remains seated without disturbing the seated packer.

7. An apparatus for making production tests in deep well drilling comprising an outer pipe, a packer having a passage therethrough and which is capable after having once been seated in a well of retaining its sealing effectiveness independently of forces exerted upon it by the outer pipe, means cooperating with the packer forming a conduit extending from the bottom of the packer upwardly within the outer pipe, means providing a movable connection between the packer and the outer pipe enabling the outer pipe to be moved while the packer remains seated without disturbing the seated packer, there being discharge ports in the outer pipe permitting circulation to be maintained within and without the outer pipe while the outer pipe is being moved.

8. An apparatus for making production tests in deep well drilling comprising an outer pipe, a packer having a passage therethrough and which is capable after having once been seated in a well of retaining its sealing effectiveness independently of forces exerted upon it by the outer pipe, means cooperating with the packer forming a conduit extending from the bottom of the packer upwardly through the outer pipe, and means including an anti-friction bearing providing a rotatable connection between the packer and the outer pipe enabling the outer pipe to be rotated while the packer remains seated without disturbing the seated packer.

9. An apparatus for making production tests in deep well drilling comprising an outer pipe, a packer having a passage therethrough and which is capable after having once been seated in a well of retaining its sealing effectiveness independently of forces exerted upon it by the outer pipe, means cooperating with the packer forming a conduit extending from the bottom of the packer upwardly within the outer pipe, means providing a rotatable connection between the packer and the outer pipe enabling the outer pipe to be rotated while the packer remains seated without disturbing the seated packer, and means associated with the packer adapted to engage the wall of the well to hold the packer from being rotated under the influence of the outer pipe.

10. An apparatus for making production tests in deep well drilling comprising an outer pipe, a packer having a passage therethrough and which is capable after having once been seated in a well of retaining its sealing effectiveness independently of forces exerted upon it by the outer pipe, means cooperating with the packer forming a conduit extending from the bottom of the packer upwardly within the outer pipe, means providing a rotatable connection between the

5 packer and the outer pipe enabling the outer pipe to be rotated while the packer remains seated without disturbing the seated packer, there being ports provided in the outer pipe

5 permitting circulation to be maintained within and without the outer pipe while the outer pipe is being rotated.

10 11. An apparatus for making production tests in deep well drilling comprising a packer having a passage therethrough, an inner pipe communicating with said passage and serving by its weight to cause the packer to maintain its sealing effectiveness while seated in a well, an outer pipe rotatably disposed about the inner pipe above the packer so as to be capable of being rotated relatively to the inner pipe and packer, and means connecting the outer pipe to the packer whereby the packer may be lowered to its seat and removed therefrom by the outer pipe.

15 12. An apparatus for making production tests in deep well drilling comprising a packer having a passage therethrough and being downwardly reduced in size, means cooperating with the packer forming a conduit extending from the bottom of the packer upwardly, and an outer pipe disposed about said conduit and movable relatively to said packer.

20 13. An apparatus for making production tests in deep well drilling comprising a packer having a passage therethrough and having a downwardly tapered external seating surface, means cooperating with the packer forming a conduit extending from the bottom of the packer upwardly, and an outer pipe disposed about said conduit and movable relatively to the packer.

25 14. An apparatus for making production tests in deep well drilling comprising a packer having a passage therethrough and having a downwardly tapering external seating surface, means cooperating with the packer forming a conduit extending from the bottom of the packer upwardly, and an outer pipe disposed about said conduit and rotatably connected to the packer.

30 In testimony whereof I have signed my name to this specification.

35 50 GEORGE A. MACREADY.
